UNITED STATES PATENT OFFICE.

GEORGE W. BEADLE, OF NEW ROCHELLE, NEW YORK, ASSIGNOR, BY MESNE ASSIGNMENTS, TO COLUMBIA GRAPHOPHONE MANUFACTURING COMPANY, OF BRIDGEPORT, CONNECTICUT, A CORPORATION OF DELAWARE.

COLLAPSIBLE VIBRATION-ABSORBING SUPPORT.

1,372,991.

Specification of Letters Patent.

Patented Mar. 29, 1921.

Application filed November 8, 1917. Serial No. 200,961.

To all whom it may concern:

Be it known that I, GEORGE W. BEADLE, a citizen of the United States of America, and a resident of New Rochelle, New York, have invented a new and useful Improvement in Collapsible Vibration-Absorbing Supports, which invention is fully set forth in the following specification.

This invention is intended primarily for supporting phonographs when in use upon railway trains or automobiles, but may be used for typewriting-machines and in other service where the instrument is to be protected from the jolts or jars due either to travel or to the vibrations of near-by machinery, etc.

The invention comprises broadly a framework carrying and positioning a plurality of shock-absorbing devices. More specifically the invention comprises two cross-arms centrally pivoted together, and carrying at their ends suitably-cushioned seats for the corners of the phonograph or other device to be supported, and provided also with suitable cushioning-devices to rest upon a table or other support without injury to the latter. The invention also comprises the feature of construction and arrangement hereinafter set forth and claimed.

The invention may be embodied in different concrete forms; but for the sake of clearness the following specification and the accompanying drawings set forth one preferred embodiment for use with the commercial dictation-machine known as the dictaphone. In said drawings:

Figure 1 represents a front elevation of the device, the phonograph being conventionally indicated in outline only;

Fig. 2 is a plan of the same device, the phonograph being removed; and

Fig. 3 represents, on a larger scale, a detail partly in vertical section.

Referring to these drawings: The framework consists of the two cross-arms 1 and 2, shown as two flat horizontal bars, pivoted together at their center, as by a rivet 3; and near each end of one member (as 2) is an offset 4, so that all four outer ends will lie in the same horizontal plane. Preferably there will be a definite predetermined limit for the movement of the two arms when opening, as by a curved slot 5 in one member and a depending pin 6 in the other,—it being

understood that when opened into their predetermined extreme positions (as indicated in Fig. 2), the four ends of the arms will be properly positioned for receiving the four corners of the particular phonograph (or other instrument for which the particular framework is designed).

Above the end of each arm is secured a boss 7, preferably circular; and beneath the same is secured a cushion 8, preferably of rubber, suitably held in place as by a headed screw 9 passing through a washer 10 and threaded into the end of the cross-arm (and into its boss also, if desired).

One or more convolutions of the lower end of a comparatively-stiff upright helical-spring 11 are engaged snugly around the boss 7, where they are secured in place in any suitable manner, as by solder. The upper end of each spring 11 carries a seat 12 for one corner of the dictaphone. This seat is shown as a substantially-rectangular plate having around two sides an upturned flange, to provide a three-sided concave corner to fit the convex corner of the dictaphone; and the central portion of said seat is cut away to leave an aperture 13 with a plurality of integral fingers 14, here shown as three in number, which are then bent down to engage within the helix of the spring 11, where they are suitably secured to the spring, as by being bent slightly around the wire constituting the convolutions thereof, or by solder or the like.

In traveling, and for shipment, the two arms are folded up as near parallel as possible, so as to occupy less space than when opened out. In order to use the device, the arms are opened out as far as the slot and pin (5 and 6) will permit, as indicated in Fig. 2, and then placed on a table or other suitable support; and then the phonograph is seated with its four corners resting in the four properly-positioned seats 12.

The cushions 8 are primarily intended to prevent injury to the surface of the support on which they rest; but they coöperate with the springs 11 in absorbing shocks and jars, which would be especially objectionable in the case of a machine for recording or reproducing sounds.

One form of the invention has thus been described with full detail, but only for the sake of clearness, since the invention is not

- limited to the precise construction and arrangement here set forth, but might be embodied in various forms, and parts might be transposed or inverted or otherwise modified within the spirit of the invention. For instance, although the drawings show the framework made up of two arms centrally pivoted together; yet it is obvious that they might be pivoted otherwise than centrally, and that there might be a greater number of arms than two; also that the shock-absorbers might be provided at only two of the adjacent corners of a rectangular device, reliance being had upon the lateral rocking thus provided for absorbing some part of the shock. But the symmetrical form set forth, with the two centrally-pivoted cross-arms and the four shock-absorbers, is believed the most desirable arrangement.
- 10 The invention having been thus described, what is claimed is—
1. In a collapsible support, the combination with two pivoted cross arms, of vibration-absorbing means at each terminal thereof, each said means comprising a cushion and boss secured on opposite sides of the terminal, an upright helical spring secured to said boss, and a centrally apertured corner-supporting seat resting upon said spring
- 15
- 20
- 25

and having downturned fingers secured to 30 the same.

2. In a shock-absorbing support, the combination of a pair of members pivoted together between their terminals, means carried by each terminal comprising on one side 35 thereof a cushion pad and on the other side a spring and an article receiving cap mounted on the spring, and a single means for maintaining the pad and spring in axial alinement.

40

3. In a shock-absorbing support, the combination of a pair of members pivoted together between their terminals, each terminal being provided with a block on its upper side, a solid cushion on the other side of the 45 terminal beneath said block, means passing through the cushion and the terminal into the block for securing the three members in fixed relation, a coil spring centered over said block, and an article-receiving cap supported by said spring.

45

In testimony whereof I have signed this specification in the presence of a subscribing witness:

GEORGE W. BEADLE.

Witness:

J. S. GRIFFITH.
